DESIGN FOR A COMBINED YO-YO, TOP, AND WHISTLE

Henry E. Elfmont, Patchogue, N. Y.

Application January 16, 1945, Serial No. 117,455

Term of patent 3½ years

(Cl. D34—15)

To all whom it may concern:

Be it known that I, Henry E. Elfmont, a citizen of the United States, residing at Patchogue, in the county of Suffolk and State of New York, have invented a new, original, and ornamental Design for a Combined Yo-Yo, Top, and Whistle, of which the following is a specification, reference being had to the accompanying drawing, forming part thereof.

In the drawing:

Fig. 1 is a side elevational view of a combined yo-yo, top, and whistle, showing my new design.

Fig. 2 is a front elevational view of the combined yo-yo, top, and whistle shown in Fig. 1.

I claim:

The ornamental design for a combined yo-yo, top, and whistle, substantially as shown.

HENRY E. ELFMONT.
